UNITED STATES PATENT OFFICE.

CHARLES FENNELL, OF CYNTHIANA, KENTUCKY.

PHOTOGRAPHIC DEVELOPING APPARATUS.

No. 834,463.

Specification of Letters Patent.

Patented Oct. 30, 1906.

Application filed January 12, 1906. Serial No. 295,772.

To all whom it may concern:

Be it known that I, CHARLES FENNELL, a citizen of the United States, residing at Cynthiana, in the county of Harrison and State 5 of Kentucky, have invented certain new and useful Improvements in Photographic Developing Apparatus, of which the following is a specification.

My invention relates to improvements in 10 apparatus for developing photographic films, and more particularly to that class of such apparatus that embody a casing designed to contain the photographic films wound up upon a spool and into which the developer 15 is introduced to act upon the film.

The primary object of my invention is to 20 provide an apparatus of this character which will permit the developing solution to quickly gain access to and affect all parts of the film, 25 so that the operation of developing the same will be greatly expedited.

With this and other objects in view, as will 25 more fully appear as the description proceeds, my invention consists in the constructions, arrangements, and combinations of 30 parts hereinafter fully described, and set forth in the appended claims.

For a full description of the invention and 35 the merits thereof and also to acquire a knowledge of the details of construction of the means for effecting the result reference 40 is to be had to the following description and accompanying drawings, in which—

Figure 1 is a perspective view illustrating 45 the improvements of my invention. Fig. 2 is a detail perspective view of a partition employed. Fig. 3 is a view illustrating a portion of the flexible curtain upon which the photographic film is wound. Fig. 4 is a longitudinal sectional view illustrating the parts 50 preparatory to commencing the operation of winding the photographic film and the curtain together upon one of the shafts. Fig. 5 is a similar view showing the position of the parts with the operation concluded.

Corresponding and like parts are referred 55 to in the following description and indicated in all the views of the drawings by the same reference characters.

Referring to the drawings, the numeral 1 60 designates the casing of the apparatus, which is light-proof, and in the present instance it is oblong, as shown. Its upper edges are stepped on their inner walls, and the lid 2 of the casing is correspondingly formed to fit 65 said edge so as to insure a light-proof struc-

ture. The casing 1 is divided into two compartments by means of a transverse partition 3, which fits the under side of the lid snugly, and the partition 3 may be detachable from the casing and inserted in the same in grooves or guideways 1^a, so as to effectively divide or separate one compartment of the casing from the other. The two compartments of the box are for convenience 70 designated A and B.

The partition 3, it is to be especially noted, is constructed in telescopic sections, so that the lower portion may move up into or upon the upper portion to produce an opening 4 75 between the compartments A and B at the bottom of the casing underneath the partition in its telescopic condition. In the present instance this telescopic arrangement of the partition is provided for by constructing 80 the partition of two spaced-apart upper members or sections 3^a and a lower section 3^b, which is fitted between the two spaced-apart sections and is provided at its upper edge with an actuating-rod 5, which extends 85 through an opening 6 in the upper connecting edge of the two spaced members or sections 3^a. Hence by manipulating the actuating-rod 5 the lower section 3^b may be moved from its lower extended position, 90 where it rests upon the bottom of the casing, upwardly into the space between the other two sections 3^a and produce the opening before mentioned. The actuating-rod or handle 5 also extends through a light-proof opening 7 in the lid 2 of the casing.

In the compartment B of the casing 1 there is mounted a transverse shaft 8, provided with an operating-handle 9 on the outside of the casing and designed to receive a 95 curtain 10, upon which the film to be developed is wound. The curtain 10 of my invention consists in the present instance of flexible parallel strips 11, preferably of rubber, connected together with a series of transverse strips 12, preferably of metal, connected at their ends to the flexible longitudinal strips 11 in any desired manner. The compartment B is provided at one end of the casing with a light-proof door 13, whose 100 edges are preferably stepped and fit correspondingly-formed edges in the wall of the casing 1. The aperture produced by opening the door 13 is intended for the insertion of the developing solution into the compartment B.

The compartment A contains a transverse

shaft 14, provided at one end with a handle 15 on the outside of the casing 1, and the said compartment also contains two lugs or studs 16 and a holder 17 for the film-spool. The 5 spool-holder is preferably secured to the partition 3 near the upper edge of the latter.

In the practical operation of my invention the curtain 10 is wound up upon its shaft in the compartment B, with the exception of 10 one end, which is provided with hooks 18, that are engaged with the studs or lugs 16 in the compartment A, the lower end of the partition being raised, so as to permit such end of the curtain to pass under the shaft 14. 15 The spool or film is then placed in the holder 17 and is wound around the shaft 14 until the ordinary protective black paper has been nearly wound up on said shaft, this point being ordinarily indicated by suitable indicia 20 on the paper. Then the edge of the curtain 10, that has been held by the studs or lugs 16, is disengaged therefrom and is hooked upon the shaft 14. This operation is performed thus far with the lid 2 of the casing 25 removed. The said lid 2 is now placed on the casing 1, so as to exclude all light therefrom, and the shaft 14 is again turned, so as to complete the winding of the film thereon, while at the same time it effects the winding 30 of the curtain upon said shaft. This operation is continued until the entire curtain and film have been wound upon the shaft 14, it being understood by those versed in the art to which this invention appertains that the 35 curtain is so interwound with the film as to effectively protect the sensitive side of the film from scratches. The partition 3 is then extended, with its lower section close against the bottom of the casing 1, so as to exclude 40 all light from the compartment A, and the door 13 is then opened and the developing solution poured into the compartment B. The door 13 is then again closed, and the partition is opened to allow the developing solution 45 to flow from the compartment B into the compartment A. When this has been effected, the partition 3 is again lowered to cut off communication between the two compartments, and the handle or crank of the 50 shaft 14 is then turned until the film has been developed.

It is to be particularly noted that my invention provides an arrangement of parts whereby the curtain upon which the film is 55 wound does not have to be of any material that will exclude actinic light, as the light is excluded from the casing 1 and from the compartment A thereof by the novel arrangement of parts. Hence the curtain 10 may be 60 formed of any material which will admit actinic light and, as shown in the present instance, may be formed with a considerable open area, so as to permit the developing solution to gain quick access to the film and de- 65 velop the same, and thereby shorten the op-

eration of developing. While I have shown the curtain 10 as constructed of two longitudinal flexible strips connected together by spacing-bars, it is manifest that my invention is not limited thereto and that any curtain 70 may be employed within the purview of my invention that will admit actinic light. Hence the entire surface of the film is not covered by the curtain necessarily during the operation of developing, and, as before 75 stated, the developing solution can gain quick access to affect the sensitive film.

Having thus described the invention, what is claimed as new is—

1. A developing apparatus for photographic films, comprising a light-proof casing, an adjustable partition dividing said casing into compartments and providing a means for communication between said compartments, a spool-holder for a spool of photographic film mounted in one of said compartments, a protective curtain, a shaft in said compartment, means for winding the curtain and film together upon said shaft, and means for admitting the developing solution into said compartment to act upon said film. 80

2. A developing apparatus for photographic films, comprising a light-proof casing, an adjustable partition mounted in said casing and designed to divide the same into two separate and distinct compartments, a spool-holder in one of said compartments, for a spool of photographic film, a protective curtain, means for winding the said curtain 95 and film together over the spool-holder in one of said compartments, means for admitting a developing solution into the other compartment, and means for subsequently adjusting the partition to admit said solution from the 100 compartment into which it is admitted to the other compartment containing the curtain and film. 105

3. An apparatus of the character described, comprising a casing, an adjustable partition dividing said casing into two compartments, shafts in each of said compartments, a spool-holder in one of said compartments, means for adjusting said partition whereby to establish communication between 110 the said compartments, a flexible curtain designed to be supported on one of said shafts, a spool-holder in one of said compartments, means for winding a photographic film carried by said spool-holder from the latter to 115 the shaft in the same compartment and for winding simultaneously therewith the curtain on said shaft from the other shaft, and means for introducing the developing solution into one of said compartments with the 120 partition closed and then subsequently introducing the solution into the other compartment by opening the partition between the two as and for the purpose set forth. 125

4. An apparatus of the character de- 130

scribed comprising a casing, a partition dividing said casing into two compartments, said partition being provided with a telescoping section whereby communication 5 may be established between the two compartments, an actuating-rod for said section, said rod extending through the top of the casing whereby the section may be raised and lowered from the outside of the casing, a 10 winding-shaft mounted in each of said compartments, a spool-holder in one of said compartments, the other compartment being provided with an opening for the insertion of

the developing solution and a closure for said opening, and a flexible winding-curtain 15 which will admit actinic rays and designed to be wound from one shaft to the other together with a film mounted on said spool-holder, as and for the purpose set forth.

In testimony whereof I affix my signature 20 in presence of two witnesses.
